UNITED STATES PATENT OFFICE

CLAES WM. BOMAN, OF NEW YORK, N. Y.

CIGAR ROLLING OR WRAPPING MACHINE.

SPECIFICATION forming part of Letters Patent No. 393,609, dated November 27, 1888.

Application filed August 2, 1888. Serial No. 281,780. (No model.)

To all whom it may concern:

Be it known that I, CLAES WM. BOMAN, of the city, county, and State of New York, have invented certain new and useful Improvements in Cigar Rolling or Wrapping Machines, of which the following is a specification.

The invention about to be described consists of improvements on the cigar-wrapping machine described and illustrated in my application for Letters Patent, Serial No. 268,989, filed March 30, 1888, on which I have since obtained Letters Patent No. 388,174, dated August 21, 1888, some of these improvements—as, for example, those having reference to the cutter and to the presser—being of more general application to cigar-wrapping machines.

The improvements can best be explained and understood by reference to the accompanying drawings, in which—

Figure 1 is a plan view. Fig. 2 is a rear elevation. Fig. 3 is a perspective view of the head-stop. Fig. 3^a is a plan of the cutter and the adjoining end of the thimble with the paste-receptacle removed. Fig. 4 is a section of same on line 4 4, Fig. 2. Figs. 5 and 6 are detail views of the standards. Fig. 7 is a detail view of the spreader.

A is the driving shaft journaled in standards B C, and driven from any suitable prime mover, in this instance by friction-gearing consisting of the friction-wheel *m'*, mounted on shaft A, and rubber-faced friction-disk *n*, mounted loosely on an eccentric, *n'*, fast to the cross-rod *o*, which is to slide longitudinally in standards *p*, in which it is also capable of rotation, being for this purpose provided with a handle, *o'*. The friction-disk *n* is joined to a pulley, *n*², driven from some suitable source.

The object of the eccentric mounting of the disk *n* is, that it may be brought into or out of contact with the wheel *m'* in order that the shaft A may be revolved or not, as desired. The longitudinal movement of the rod *o* allows the speed of the shaft A to be varied by varying the distance of the disk *n* from the center of the wheel, and also permits the direction of revolution of the shaft A to be reversed by drawing the disk from one side of the axis of the wheel to the other side. In this way the workman has the movement of the shaft A and of the parts to which it gives motion en-

tirely under his command. Upon the shaft A is the main driving-pinion *a*.

D are the cigar-wrapping rolls, similar in construction and arrangement to those described in my aforesaid patent, their shanks passing through slots *b c*, formed in the standards B C. They carry pinions *d*, which mesh with pinion *a*, and they are held together by an encircling spring, E.

F is the spreader for spreading apart the rolls. It is centered on shaft A, is provided with cam-slots *f*, through which the shanks D' pass, and is normally held by a spring, *e*, in a position in which the rolls are closed.

When the cigar is placed in the mold-space formed by the rolls, its point or tip projects out from this space and beyond the free ends of the rolls D. This projecting tip is received in and supported by a thimble, J, having in its upper face an approximately conical cavity, *j*, of the shape of the cigar-tip. This thimble is carried by a head-stock, K, which can slide longitudinally on a guide, K', so that it may be moved back to uncover the free ends of the rolls and to permit the cigar or "filler" to be inserted endwise between said rolls.

Thus far the machine, with the exception of the means for varying the speed and changing the direction of rotation of the shaft A, is similar to the machine described in my aforesaid patent. It is desirable, however, that the operation of moving back the thimble and spreading apart the rolls should be accomplished by one movement, and it is also desirable that when the parts, after having thus been moved, are released they should return to their original position. To this end I connect said parts in such manner that both of them shall be actuated by or from a single lever, handle, or treadle. A variety of mechanisms, manifestly, can be employed for this purpose. That shown in the drawings consists of an angle or elbow lever, K², pivoted to a bracket on the under side of the table or base of the machine, with one of its arms extending up through an opening in said base and provided with a slot, *k*', which is entered by a pin, *k*, projecting laterally from the thimble-stock K. A spring, *k*², draws the thimble-stock normally into a position in which the thimble will be held in operative position with

respect to the rolls, and adjustable stop k^2 , against which the thimble stock brings up, determining the distance at which the thimble shall stand from the free end of the rolls. 5 This feature is of value whether the thimble-stock and spreader be connected together or not. I prefer, however, to connect them together, because, as before indicated, they both can then be operated by one movement and by 10 one instrumentality. To accomplish this, I provide a slide-rod, l , supported in bearings l' at one end and jointed at the other end to a pivoted cam-lever, l^2 , the cam-face of which is under the handle F' of the spreader F . A spring, 15 F , draws this rod in a direction in which the cam does not affect the spreader. Upon the rod l is a tappet, l^1 , which extends into the path of movement of the head of the pin k . This tappet l^1 is adjustable on the rod l , and 20 is held in its adjusted position by a set-screw. When the lever K^2 is, by a treadle or other means, moved in a direction to draw back the thimble-stock, the pin k at the proper time will strike the tappet l^1 , thus drawing back 25 the rod l with the effect of moving the cam-lever l^2 in a direction in which it will come under and lift the handle F' and cause the spreader F to spread the rolls apart. As soon as the lever K^2 is released, the parts will at 30 once resume their original position.

For the purpose of keeping the tip of the cigar well in the thimble, which is essential to the formation of a good tip or point, I employ a sliding presser, G , which passes axially 35 through shaft A , and is influenced by a light spring, g , to press constantly against the butt-end of the bunch or filler, thus holding the latter tight against the point of the thimble.

When the cigar is wrapped and finished, this 40 presser by its handle G' can be pressed still harder against the cigar, thus forcing it hard up into the thimble. If under these conditions the cigar be revolved a few times in the thimble, the point or tip of the cigar will be 45 "polished," and at the same time closed tightly. Afterward, when the rolls are spread apart and the thimble-stock is moved away from the rolls, the presser can be used also as an ejector to expel the cigar from between the rolls.

50 H is the table of the machine, overhanging at its inner end the top rolls, between which the wrapper enters. A hinged tucking-blade, I , retracted by a spring, I' , is provided for the purpose of tucking the front end of the wrap- 55 per down between these rolls.

The cutter for shaping the point or tip end of the wrapper is carried by the thimble-stock. The stationary member of the cutter or shears is formed by the piece m . The other and mov- 60 able member is the cutter-plate L , having a cutting-edge of a shape to co-operate with piece m . The movable cutter-plate in this instance is mounted on a stem or standard, L' , vertically movable in the thimble-stock and actu- 65 ated to move up and down by a pivoted elbow-lever, L^2 , with which it has a pin-and-slot connection. The more essential feature of this

cutter is the shape of its cutting-edge and the relation in which that edge stands to the point of the thimble. It will be noted that the edge 70 consists of the straight or substantially straight part 1 and the approximately ogee-curved part 2 , and that the straight part 1 extends diagonally across the end or point of the thimble. This construction and arrangement are mate- 75 rial, the result being that the wrapper is cut in such manner that it will wind around the point of the filler in the easiest possible way, will cover up the extreme point, and will not wrinkle; nor is there liability of the wrapper 80 opening at the point afterward—a trouble which has been frequently experienced hereto-fore. The inclination at which the cut is made seems to take away all resistance from the leaf or wrapper and allows it to remain perma- 85 nently where the thimble places it.

On the cutter-standard L' is a tongue, s , which, when the cutter is down, (as it will be at the time the point of the cigar is being wrapped,) closes the top of the thimble, and 90 serves to guide the wrapper and to prevent the latter from wrinkling as it is fed into the thimble.

I may under some circumstances use in fin- 95 ishing the tip of the cigar a paster for supply- ing the paste which usually is applied to the tip end of the wrapper. For example, a paste- reservoir, M , may be provided mounted on the thimble-stock, and communicating by a suit- able passage or duct, t , with the interior of the 100 thimble. The supply of paste from the reser- voir to this duct can be regulated by a valve or other suitable means.

Having described my improvements and the 105 manner in which the same are or may be car- ried into effect, what I claim herein as new and of my own invention is—

1. In a cigar wrapping or rolling machine, the combination of the cigar-receiving rolls D , the shaft A , the gearing connecting said rolls 110 and shaft, the friction-wheel m' on shaft A , the rotatable and longitudinally-movable cross-rod o , and the friction-disk n , eccentrically mounted and rotatable upon the rod o , under the ar- 115 rangement and for operation as hereinbefore set forth.

2. The combination, with spring-closed yield- 120 ing power-driven rolls inclosing a cigar-mold space, access to which is had from one end of the rolls, and mechanism for spreading said rolls apart, so as to open the mold at that end, of a head-stock movable to and from said end, a spring by which said head-stock is drawn toward the rolls, a stop for limiting this move- 125 ment of the head-stock, and a tip-forming thimble carried by said head-stock, substantially as hereinbefore set forth.

3. The combination of the power-driven cigar-receiving rolls, the spreader for said rolls, the thimble-stock movable to and from the 130 rolls, said spreader and thimble-stock being spring-actuated in the direction requisite to cause the rolls to close and the thimble-stock to close up toward or against the rolls, and

mechanism connecting said thimble-stock and spreader, whereby the movement of the thimble-stock against the stress of its spring shall cause a corresponding movement of the spreader, as and for the purposes hereinbefore set forth.

4. The combination of the rolls D, the thimble-stock, its controlling-spring, the pin k, the tappet l, the rod l, the spring l, the cam-lever 10 l, and the spreader, substantially as and for the purposes hereinbefore set forth.

5. In combination with the thimble, the cutter consisting of the stationary and movable members L m, having cutting-edges shaped as 15 indicated at 1 2, and located with relation to

the point of the thimble substantially as and for the purposes hereinbefore set forth.

6. In combination with the stationary and movable members of the cutter, the thimble and the finger carried by the moving member 20 of the cutter, and adapted to operate in connection with the thimble substantially as hereinbefore set forth.

In testimony whereof I have hereunto set my hand this 21st day of July, 1888.

CLAES WM. BOMAN.
